UNITED STATES PATENT OFFICE

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS

MINING MACHINE

Application filed January 3, 1932, Serial No. 528,864. Renewed January 26, 1931.

This invention relates to improvements in kerf cutting mining machines and more particularly to that type of kerf cutting machines commonly called over-cutting machines. Such machines are usually mounted on wheels and supported on the mine track both while moving from place to place and while forming a kerf, and are provided with cutting mechanism extending therefrom so as to cut at points between the mine floor and the roof.

The principal object of the present invention is to provide a mechanism of the class above described suitable for working in low seams of coal and having means whereby the cutting mechanism may be tilted both on a longitudinal and a transverse axis. Means are also provided for raising or lowering the cutting mechanism so as to cut at various heights. The invention may best be understood by reference to the accompanying drawings, in which:

Fig. 1 is a top plan view of a mining machine constructed in accordance with my invention.

Fig. 2 is a view in side elevation of the machine drawn to a somewhat larger scale than that shown in Fig. 1.

Fig. 3 is a vertical cross-section of the machine taken on line 3—3 of Fig. 1.

Fig. 4 is a horizontal section taken on line 4—4 of Fig. 3.

Fig. 5 is a detailed cross-section of a portion of the driving mechanism, taken on line 5—5 of Fig. 1.

Fig. 6 is a detailed cross-section of a portion of the driving mechanism taken on line 6—6 of Fig. 1.

The main elements of the machine comprise a horizontally extending cutting mechanism A supported on a turntable B at the forward end of the machine. Said turntable B is mounted on a sub-frame C so as to rotate in a substantially horizontal plane. The sub-frame C is trunnioned on a longitudinal axis to a frame member D (see Fig. 4) which in turn is pivotally mounted between truck members E, E, to rock on a transverse axis. By means of the several pivotal connections above described, details

of which will be hereinafter more fully described, it will be seen that the cutting mechanism A may be fed to the coal in a variety of positions which may be controlled by tilting the sub-frame C on its longitudinal axis with respect to the frame member D, in which case the sides of the cutter arm will be tilted on its longitudinal axis so as to cut an inclined kerf higher at one end than at the other end of the cut. The cutter arm may also be tilted so that its outer end is raised or lowered, by tilting the sub-frame C and frame D as a unit with respect to the truck members E, E, on the transverse pivotal connection between said frame D and said truck members.

Referring now to details of construction of the machine, the cutting mechanism A comprises a cutter arm 10 having a suitable guide-way 11 for supporting a cutter chain (not shown) of any approved pattern. The cutter arm is secured in a head frame 12 by means of bolts 13, 13. A plurality of upright supporting guide members 14, 14, are mounted on the turntable B. In the embodiment illustrated, three such supports are shown. The head frame 12 is movable vertically with respect to said guide members 14, 14 and mechanical means are provided for raising or lowering said support which comprise a plurality of pinions 16, 16, carried by the head frame and engaging suitable racks 17, 17, mounted on the supports. These pinions are mechanically operated by means which will hereinafter be described.

The sub-frame C is provided at its front end with a trunnion 23 pivotally engaged in a bearing 24 carried by frame members 25, 25, extending forwardly from and integral with the frame member D on opposite sides of the sub-frame C below the turntable B (see Fig. 4). The trunnion 23 is preferably hollow, as shown, to afford lightness of construction. The rear end of the sub-frame C has a trunnion 26 journaled in a bearing 27 in horizontal alignment with the forward trunnion 23 already described.

Means for tilting the sub-frame C with respect to frame D comprises a laterally extending arm 28 integral with the forward end of

trunnion 23 of sub-frame C, and having a forked end 29 in which is pivoted a vertically disposed screw jack 30. The lower end of said screw jack is threaded in an annular nut 31, seated and retained within a yoke 32, extending from one side and integral with the frame D. The nut 31 is provided with a plurality of recesses 34, 34, about its periphery for receiving a handle so as to be rotated by hand. Rotation of the nut 31 on screw jack 30 causes the sub-frame C to tilt laterally respective to frame D as desired.

The frame member D extends rearwardly from beneath the turntable B and is pivotally mounted on a horizontally disposed support 40 extending between and connecting the truck members E, E, on opposite sides of said frame. Each of the truck members E, E, comprises a supporting frame 41 having wheels 42, 42, mounted on axles 43, 43. The wheels 42 have driving connection with the motor as will be described. Means for tilting the frame D on its transverse axis is similar to that already described for tilting sub-frame C on its longitudinal axis, and comprises a screw jack 35, connected near the rear end of frame D and threaded in a rotatable nut 36 retained in a yoke 37, carried on one of the supporting frames 41 of the truck, as shown.

The operating mechanism includes a motor 50, mounted at the rear end of the frame member D and provided with an armature pinion 51 which drives a gear 52 loosely mounted on a longitudinally disposed shaft 53. The forward end of shaft 53 is journaled in the trunnion 26 of the sub-frame C. A bevel gear 54 is mounted at the forward end of said shaft and is meshed with a second bevel gear 55 carried on upright shaft 21. The arrangement is such that the shaft 21 may be driven in all positions of sub-frame C. A chain sprocket 18 is mounted on the head frame 12 adjacent the rear end of the cutter arm in position to afford operative engagement with the cutter chain. The turntable B is provided with a hub 19 journaled on a stud 20 carried by the sub-frame C. The shaft 21 is journaled in the stud 20, the upper end of said shaft extending through the sprocket wheel 18 and being feathered therein so as to provide a driving connection in any one of several heights in which the head frame 12 may be placed. The lower end of the shaft 21 is journaled in a bracket 22 formed integral with the sub-frame C. A clutch member 56 is mounted on the rear end of the shaft 53 to provide driving engagement between the gear 52 and the shaft 53 so as to connect or disconnect the cutter chain with the motor.

The mechanism for raising and lowering the head frame 12 and cutter arm carried thereby comprises a gear 58 mounted on shaft 59^a adapted to engage a pinion 59 keyed on the sprocket wheel 18. The gear 58 is shift-

able vertically, and is provided with a clutch 57, comprising a cone 58^a adapted to have driving engagement with a worm 60 when gear 58 is in mesh with pinion 59. Worm 60 drives a worm gear 61 mounted on a transverse shaft 62. The latter shaft is operatively connected to a pair of longitudinally disposed shafts 63, 63, by means of miter gears 64, 64. Pinions 16, 16, which engage the vertically disposed racks 17 for raising and lowering the cutting mechanism are mounted on shafts 62 and 63, 63, as shown. The arrangement is such that when the gear 58 is meshed with pinion 59, the cone surface 58^a will engage the worm 60 to drive the shafts 62 and 63. The motor 50 may be reversed as desired to raise or lower the cutting mechanism. The worm 60 and worm gear 61 are of the self-locking type so as to maintain the cutting mechanism at any desired position.

Another driving connection with the motor 50 comprises a gear pinion 65, adjacent the gear 52 and carried therewith. A counter shaft 67 is mounted on suitable bearings 68, 68, and has two gears 66 and 69 loosely mounted thereon, and connected together by a suitable sleeve so as to rotate as a unit. A second counter shaft 70 is mounted on suitable bearings 71, 71, 71, parallel with the counter shaft 67. A gear 72 fixed on a sleeve 73, is loosely mounted on the counter shaft 70. Gear pinion 65 is meshed with gear 66 and gear 69 is meshed with gear 72. One end of the sleeve 73 forms the sun gear 74 of a planetary speed reducing device 75, affording a reduced driving speed through planetary gears 76 and 77 to an internal gear member 78. I have shown a preferable construction of planetary gear, provided with a casing 83, loosely mounted on sleeve 73, and carrying an internal gear 84 meshed with planetary gear 76. Rotation of the casing 83 is controlled by a variable friction brake 85 to afford a variation of driving speeds through the planetary. Clutch jaws 79 are integral with an internal gear member 78, and are in position to be engaged by the clutch jaws 80 of sliding clutch member 81 loosely mounted on the counter shaft 70. Clutch member 81 is shifted by clutch collar 86. Said clutch member 81 may also be shifted to engage clutch jaws 83^a, carried by the sun gear 74, to afford a direct drive between clutch member 81 and gear 72. In order to afford a gradual initial engagement between clutch member 81 and shaft 70, a clutch 87, preferably of the ordinary cone type, is provided. The latter clutch is operated by clutch collar 88.

At the forward end of the shaft 70 is a reverse clutch mechanism 95 comprising a pair of oppositely disposed miter gears 96, 96, engaged with a miter gear 97, mounted on a transverse shaft 98. A clutch member 99 is feathered on the shaft 70 and is adapted to

be shifted in opposite directions to reverse the shaft 98. The shaft 98 is provided with suitable bearings 100, 100, and affords operative connections for several functions of the machine all at variable driving speeds, and reversible, as follows: Gearing for rotating the turntable B is shown in Figs. 3 and 5, and comprises a worm 101 loosely mounted on the shaft 98 and clutched thereto at will by a sliding clutch 108, feathered on said shaft. The worm 101 is meshed with a worm gear 102, which is integral with a gear 103 loosely mounted on the counter-shaft 67. The gear 103 is meshed with a gear 104 keyed on the hub 105 of beveled pinion 106 (see Fig. 3). Said pinion engages the annular rack 107 about the periphery of the turntable B to turn the latter. It will be noted that the pinion 106 is mounted to rotate loosely on the shaft 53 and has bearing in longitudinal alignment with the trunnions 23 and 26 of the frame C so as to afford a driving connection with the turntable in all its various positions.

A variable and reversible connection to the truck wheels 42 from shaft 98 is provided as follows: A sliding gear 110 having clutch jaws 111 on one face thereof is mounted on the shaft 98, and shiftable by clutch collar 112 (see Figs. 1 and 5). A gear 113 is keyed on a sleeve 114 adjacent said gear 110, said sleeve having clutch jaws 115 adapted to engage the jaws 111 on the latter gear, so as to be driven directly thereby when the gear 110 is in the position shown in Fig. 5. Said sleeve 33 may also be driven at a reduced speed by shifting the gear 110 longitudinally into mesh with gear 116, which is mounted integral with gear 118 on counter-shaft 117. Said gear 118 is meshed with gear 113, and the latter gear is keyed on sleeve 114. Clutch jaws 111 will then be disengaged from jaws 115 on the sleeve, and the sleeve will be driven through gears 110, 116, 118 and 113 at a reduced speed. A pinion 120 is loosely mounted on the shaft 98 adjacent sleeve 114. A sliding clutch member 121 is feathered on the sleeve 114 and is provided with clutch jaws 122 adapted to engage clutch jaws 123 integral with the pinion 120 so as to provide a driving connection between sleeve 114 and the pinion 120 when desired. A brake drum 124 is preferably mounted integral with the pinion 120 and is engaged by the friction band 125 to afford a brake for the driving wheels when desired. Pinion 120 is meshed with a gear 126 mounted on the shaft 127 extending transversely through the support 40 which support has been described as connecting the truck members E, E, and providing a pivotal bearing for frame member D. Each of the axles 43, 43, and wheels 42, 42, on both truck members E, E, is operatively connected to the shaft 127 by a plurality of reach gears 128, 128, mounted in suitable casings 129, 129, on opposite sides of the machine.

A variable and reversible driving connection from shaft 98 is also provided to a rope drum 130 mounted on the shaft 117 as follows: The sliding clutch member 121 has a pinion 131 integral therewith and adapted to be thrown into mesh with a gear 132 keyed to the shaft 117, when said clutch member is shifted out of engagement with the pinion 120 which drives the truck wheels. The purpose of said rope drum is to provide means for moving the machine along the track by means of a flexible cable or chain anchored at one end to a fixed abutment and trained over the drum 130. This method is often desirable in controlling the movement of the machine during the cutting operation, as the machine may be more often positively controlled by this means than by depending upon the traction of the truck wheels on the mine track.

The use and operation is as follows: The cutter arm 10 carrying the cutter chain may be advanced to a mine wall in any desired angular relation and at any desired speed. The cutter chain is driven independently of the truck wheels and of the turntable B on which it is mounted. In driving entries or tunnels of specified widths, longitudinally of the mine track, the machine is advanced with the cutter bar at an angle, so as to make its initial cut or sump along one side of the entry. The sumping speed is relatively low, and may be provided either through the low speed gearing connections to the truck wheels, or through the low speed connection to the rope drum 130 and anchored cable, as already described. After the machine has been sumped, forward movement of the machine is discontinued and the cutter bar may be swung so that the outer end of the cutter bar describes a substantially semi-circular arc. This movement is accomplished at a low feeding speed through the gearing arrangement for driving the turntable B. The machine may also be used for drawing pillars, or cutting a kerf alongside the track, by positioning the cutter bar so as to extend from one side of the machine, and propelling the machine at slow speed along the mine track. In all of these cutting operations it will be observed that the cutter bar may be tilted at various angles with respect to the supporting tracks, so as to accommodate the cutting to various conditions, as for instance, when the strata of coal is inclined, or when the cutter bar is not at the proper cutting angle due to unlevel mine track.

Although I have shown and described one form in which my invention may be embodied, it will be understood that many other means may be employed for accomplishing the same results, without departing from the spirit and scope of my invention. I do not therefore wish to be understood as limiting myself to the specific construction or use il-

lustrated herein excepting as specifically limited in the appended claims.

I claim as my invention:

- 5 1. In a mining machine, a wheeled support, a frame member mounted on said support, and having tilting movement thereon on a transverse axis, a turntable mounted at the forward end of said frame member, a cutter arm mounted for vertical adjustment on said turntable, a motor mounted at the rear end of said frame member and having power connections with said cutting mechanism including a vertically disposed shaft concentric with said turntable.
- 10 15 2. In a mining machine, a wheeled support, a frame member having pivotal bearing on said support to rock on a transverse axis, a second frame member having pivotal bearing on the first frame member to rock on a longitudinal axis, cutting mechanism mounted on said second frame and having angular movement with respect thereto, a motor mounted on the first frame member, a shaft operatively connected with said motor and concentric with the pivotal bearing of said second frame member, said shaft being operatively connected with the cutting mechanism whereby the latter may be driven in several positions, and a second shaft operatively connected with said motor and concentric with the pivotal bearing of said first frame member, the last named shaft having operative connection with the truck wheels.
- 20 25 30 35 40 45 50 55 60 65 70 75 80 85 90 95 100 105 110 115 120 125 130 135
3. In a mining machine, a wheeled support, a frame member pivotally connected with said support to rock on a transverse axis, a second frame member having a pivotal bearing at the front end of said first frame member to rock on a longitudinal axis, a turntable mounted on said second frame having angular movement with respect thereto, cutting mechanism mounted on said turntable, a motor mounted on the first frame member, a shaft operatively connected with the said motor and concentric with the pivotal bearing of said second frame member and operatively connected with the cutting mechanism, a gear concentric with said shaft and having operative engagement with the turntable, and gearing interposed between said loosely mounted gear and said motor whereby said cutting mechanism and turntable may be driven independently of each other, and at different speeds.
4. In a mining machine, a wheeled support, a frame member mounted on said support and having tilting movement thereon on a transverse axis, a turntable mounted at the forward end of said frame member, a cutter arm mounted for vertical adjustment on said turntable, a motor mounted at the rear end of said frame member and having power connections with said cutting mechanism including a vertically disposed shaft concentric with said turntable, and other power con-

nnections between said motor and said turntable.

5. In a mining machine, a wheeled support, a frame member mounted on said support and having tilting movement thereon on a transverse axis, a turntable mounted at the forward end of said frame member, a cutter arm mounted for vertical adjustment on said turntable, a motor mounted at the rear end of said frame member and having power connections with said cutting mechanism including a vertically disposed shaft concentric with said turntable, and means driven from said shaft for adjusting the elevation of said cutting mechanism on said turntable.

6. In a mining machine, a wheeled support movable on a trackway, a turntable mounted on said wheeled support, a chain carrying cutter arm mounted on said turntable for vertical movement with respect thereto, a motor mounted on said wheeled support, and drive connections from said motor to said wheeled support including a planetary reduction gear mechanism for propelling said wheeled support and feeding said cutter arm longitudinally of the trackway and transporting said mining machine thereover at a plurality of predetermined speeds.

7. In a mining machine, a wheeled support movable on a trackway, a turntable mounted on said wheeled support, a chain carrying cutter arm mounted on said turntable for vertical movement with respect thereto, a motor mounted on said wheeled support, and drive connections from said motor to said wheeled support including a frictionally controlled planetary reduction gear mechanism for propelling said wheeled support and feeding said cutter arm longitudinally of the trackway and transporting said mining machine thereover at a plurality of predetermined speeds including a frictionally controlled low speed.

8. In a mining machine, a wheeled support movable on a trackway, a turntable mounted on said wheeled support, a chain carrying cutter arm mounted on said turntable for vertical movement with respect thereto, a motor mounted on said wheeled support, and drive connections from said motor to said wheeled support for propelling said wheeled support and feeding said cutter arm longitudinally of the trackway in reverse directions without reversal of said motor at a plurality of frictionally controlled speeds.

9. In a mining machine, a wheeled support movable on a trackway, a turntable mounted on said wheeled support, a chain carrying cutter arm mounted on said turntable for vertical movement with respect thereto, a motor mounted on said wheeled support, and drive connections from said motor to said wheeled support for propelling said wheeled support and feeding said cutter arm longitudinally

of the trackway in reverse directions without reversal of said motor at a plurality of predetermined frictionally controlled speeds including a frictionally controlled planetary gear reduction mechanism.

10. In a mining machine, a wheeled support movable on a trackway, a turntable mounted on said wheeled support, a chain carrying cutter arm mounted on said turn-

10 table for vertical movement with respect thereto, a motor mounted on said wheeled support, and drive connections from said motor to said wheeled support for propelling said wheeled support and feeding said cutter

15 arm longitudinally of the trackway in reverse directions without reversal of said motor at a plurality of predetermined frictionally controlled speeds including a frictionally controlled plural speed planetary gear reduction mechanism and other change speed mechanism interposed between said planetary gear reduction mechanism and said wheeled support.

20 11. In a mining machine, a wheeled support movable on a trackway, a turntable mounted on said wheeled support, a chain carrying cutter arm mounted on said turn-

25 table for vertical movement with respect thereto, a motor mounted on said wheeled support, and drive connections from said motor to said wheeled support for propelling said wheeled support and feeding said cutter arm longitudinally of the trackway in re-

30 verse directions without reversal of said motor at a plurality of predetermined frictionally controlled speeds including a frictionally controlled plural speed planetary gear reduction mechanism and direction changing drive gearing interposed between

35 said planetary gear reduction mechanism and said wheeled support.

40 12. In a mining machine, a wheeled support movable on a trackway, a turntable mounted on said wheeled support, a chain carrying cutter arm mounted on said turn-

45 table for vertical movement with respect thereto, a motor mounted on said wheeled support, and drive connections from said motor to said wheeled support for propelling

50 said wheeled support and feeding said cutter arm longitudinally of the trackway in reverse directions without reversal of said motor at a plurality of predetermined frictionally controlled speeds including a frictionally controlled plural speed planetary gear reduction mechanism, other change speed mechanism interposed between said

55 planetary gear reduction mechanism and said wheeled support, and direction changing drive gearing interposed between said other change speed mechanism and said planetary gear reduction mechanism.

60 13. In a mining machine, a wheeled support, a frame member mounted on said sup-

65 port and having tilting movement thereon

on a longitudinal axis, a turntable mounted at the forward end of said frame member, a cutter arm mounted for vertical adjustment on said turntable, a motor mounted at the rearward end of said frame member, and power connections from said motor to said wheeled support to propel the latter for feeding said cutter arm longitudinally of the trackway and transporting the same there-over at a plurality of frictionally controlled speeds including a planetary gear reduction mechanism.

14. In a mining machine, a wheeled sup-

70 port, a frame member mounted on said sup-

75 port and having tilting movement thereon

80 on a longitudinal axis, a turntable mounted at the forward end of said frame member, a cutter arm mounted for vertical adjustment on said turntable, a motor mounted at the rearward end of said frame member, and power connections from said motor to said wheeled support to propel the latter for feed-

85 ing said cutter arm longitudinally of the trackway and transporting the same there-

90 over at a plurality of frictionally controlled speeds including a frictionally controlled planetary gear reduction mechanism.

15. In a mining machine, a wheeled sup-

95 port, a frame member mounted on said sup-

100 port and having tilting movement thereon

105 on a longitudinal axis, a turntable mounted at the forward end of said frame member, a cutter arm mounted for vertical adjustment on said turntable, a motor mounted at the rearward end of said frame member, and power connections from said motor to said wheeled support to propel the latter for feed-

110 ing said cutter arm longitudinally of the trackway and transporting the same there-

115 over at a plurality of frictionally controlled speeds including a frictionally controlled planetary gear reduction mechanism and power connections from said motor to said cutting mechanism including a vertically dis-

120 posed shaft concentric with said turntable.

16. In a mining machine, a wheeled sup-

125 port, a frame member mounted on said sup-

130 port and having tilting movement thereon

17. In a mining machine, a wheeled support, a frame member mounted on said support and having tilted movement thereon on a longitudinal axis, a turntable mounted at the forward end of said frame member, a cutter arm mounted for vertical adjustment on said turntable, a motor mounted at the rearward end of said frame member, and power connections from said motor to said wheeled support to propel the latter for feeding said cutter arm longitudinally of the trackway and transporting the same thereover at a plurality of frictionally controlled speeds in reverse directions without reversal of said motor including a planetary gear reduction mechanism.

18. In a mining machine, a wheeled support, a frame member mounted on said support and having tilting movement thereon on a longitudinal axis, a turntable mounted at the forward end of said frame member, a cutter arm mounted for vertical adjustment on said turntable, a motor mounted at the rearward end of said frame member, power connections from said motor to said wheeled support to propel the latter for feeding said cutter arm longitudinally of the trackway and transporting the same thereover at a plurality of frictionally controlled speeds in reverse directions without reversal of said motor including a frictionally controlled planetary gear reduction mechanism and other change speed gear reduction mechanism interposed between said planetary gear reduction mechanism and said wheeled support.

19. In a mining machine, a wheeled support, a frame member mounted on said support and having tilting movement thereon on a longitudinal axis, a turntable mounted at the forward end of said frame member, a cutter arm mounted for vertical adjustment on said turntable, a motor mounted at the rearward end of said frame member, power connections from said motor to said wheeled support to propel the latter for feeding said cutter arm longitudinally of the trackway and transporting the same thereover at a plurality of frictionally controlled speeds in reverse directions without reversal of said motor including a frictionally controlled planetary gear reduction mechanism, other change speed gear reduction mechanism interposed between said planetary gear reduction mechanism and said wheeled support, and direction changing drive gearing interposed between said other change speed mechanism and said planetary gear reduction mechanism.

Signed at Chicago in the county of Cook and State of Illinois, this thirtieth day of December, 1921.

CHARLES E. DAVIS.
